US0D1096463S

(12) **United States Design Patent** (10) **Patent No.:** **US D1,096,463 S**
(45) **Date of Patent:** **** Oct. 7, 2025**

(54) **MEASURING DEVICE FOR STAIR TREAD**

(71) Applicant: **Jiayi Lai**, Qingyuan (CN)

(72) Inventor: **Jiayi Lai**, Qingyuan (CN)

(**) Term: **15 Years**

(21) Appl. No.: **29/980,598**

(22) Filed: **Dec. 26, 2024**

(30) **Foreign Application Priority Data**

Oct. 21, 2024 (CN) 202430663146.9

(51) **LOC (15) Cl.** **10-04**

(52) **U.S. Cl.**

USPC **D10/64**; D10/65; D10/71

(58) **Field of Classification Search**

USPC D10/61-65, 69-75; D24/140; D18/34.9, D18/9; D19/135, 156, 133, 123, 115; D15/122, 125, 126, 127, 138, 140; D8/70, 72, 74, 402, 499, 71

(57) **CLAIM**

The ornamental design for a measuring device for stair tread, as shown and described.

DESCRIPTION

FIG. 1 is a perspective view of a measuring device for stair tread, showing my new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

All the broken lines in the drawings depict portions of the measuring device for stair tread that form no part of the claimed design.

1 Claim, 5 Drawing Sheets
